UNITED STATES PATENT OFFICE.

RAFAEL ALCOLEA, OF NEW ORLEANS, LOUISIANA.

SWITCH-POINT OPERATOR.

1,229,566.

Specification of Letters Patent. Patented June 12, 1917.

Application filed February 24, 1915. Serial No. 10,340.

To all whom it may concern:

Be it known that I, RAFAEL ALCOLEA, a citizen of the United States of Mexico, residing at New Orleans, in the parish of Orleans and State of Louisiana, have invented certain new and useful Improvements in Switch-Point Operators, of which the following is a specification.

My invention relates to railway switches and more particularly to improvements for automatically operating the switch point or points from a vehicle moving on a railway track.

The primary object of my invention is to provide improved means associated with a railway track switch point whereby the switch point may be moved from a vehicle or car moving on the track.

Another object of my invention is to provide improved means on the car actuatable by the motorman coacting with the means on the track whereby the position of the switch point may be changed as desired.

Another object of my invention is to provide means for automatically disengaging the actuating means carried by the car when it has performed its function.

With the above and other objects in view my invention resides preferably in the construction, combination, and arrangement of parts as hereinafter set forth in the specification and illustrated in the accompanying drawings, in which—

Figure 1 is a vertical sectional view through the switch actuating means carried on the vehicle.

Fig. 2 is a top plan view of a switch operating contact arrangement wherein electricity is utilized as a medium of operation, and

Fig. 3 is a longitudinal sectional view of one of the circuit closers taken on the line 3—3 of Fig. 2.

Fig. 4 is a plan view of part of the mechanism shown in Fig. 1.

Similar reference characters indicate similar parts throughout the various views of the drawings.

Referring more particularly to the drawings in which the preferred form of my invention is illustrated, the numeral 1 indicates the rails of a railway track, the floor 2 of a street railway vehicle being indicated in Fig. 1.

Reference is now directed to Fig. 2 in which a switch point is indicated by the

numeral 4 the switch being pivoted at 5 and may be of the usual construction resorted to in street railway practice. The rails of a spur track are indicated at 6. Only one switch point has been indicated, although two switch points may be employed, but it will suffice to indicate the preferred structure, operation, and advantages of my invention.

The operating mechanism for the switch point is preferably placed at any desired distance in advance of the switch point 4 and comprises a plurality of longitudinally disposed parallel channel members designated 41 and 42, respectively. The channel members 41 and 42 are disposed either between the rails 1 or outside and laterally thereof, the preferred location being indicated in Fig. 2 for this particular form of my invention. The said channels 41 and 42 respectively are substantially alike in construction, and are provided with abutment walls 43 and 44. The abutment walls of each of the channel members 41 and 42 respectively are extended above the upper marginal edge of the side walls of each of said channel members as shown in the drawing to provide abutments having a curved or beveled rear surface for a purpose which will hereinafter be set forth. These abutments 43 and 44 extend completely across the width of the two channel members 41 and 42 and may be cast integral therewith thus forming a structure which may be placed in position without bolts, nuts or similar fastening means.

Movable in each of the members 41 and 42 are contact blocks 47 and 48 which are adapted to be operated in a manner about 95 to be explained. In order to actuate one or the other of the blocks 47 and 48 to cause the throwing of the switch point 4, I provide an arm 22 pivoted universally at 23, the joint being rigidly held assembled by 100 bolt 23, to the floor 2 of the vehicle. The said arm 22 when in an operative position extends downwardly from the under surface of the body 2, at an angle substantially as shown in Fig. 1. The lower extremity 105 of the arm 22 is provided with an angularly disposed extension 24 for the purpose of engaging one or the other of the blocks 47 and 48 in a manner which will hereinafter become apparent. The arm 22 intermediate 110 its pivoted end and lower extremity is provided with a lug 25, the said lug 25 being

preferably arcuate in contour as illustrated to advantage in Fig. 1. The position of the lug 25 is preferably as shown in the drawing, that is, adjacent the lower extremity of the arm 22 and its purpose will be more fully described hereinafter.

Actuating means is provided for the arm 22 which includes a casing 26 mounted vertically on the floor 2 of the vehicle and braced in said vertical position by any suitable bracket arm. An operating staff 28 extends vertically through the casing 26, and is adapted for vertical and rotary movement therein. The lower extremity of the operating staff 28 is pivotally connected at 29 to a relatively movable section 28' of the staff 28, the lower extremity of said pivoted portion 28' being pivotally connected as shown at 29' with a link 30 which link is in turn connected at 31 to the arm 22. The staff 28 is provided at its upper extremity with an operating handle 32 which facilitates the manipulation of the device.

The normal position of the arm 22 is as shown in Fig. 1 and it will be noted that in this view the arm 22 is very nearly parallel to the floor 2 of the vehicle.

In order to provide means for the supporting of the staff 28 an annular ledge 33 is provided within the casing 26 at a point midway its length, the said annular ledge 33 being of such size as to snugly embrace the operating staff 28 as shown at 34. A second bearing member is indicated at 35 and assists the bearing flange 33 in performing its function. In order to retain the operating staff in the position illustrated in Fig. 1 a helical spring 36 is provided within the casing 26 surrounding the operating staff 28, one extremity of the spring 36 bearing upon the upper face of the flange 33 and the opposite extremity of the spring 36 bearing against a collar 37 carried on the said operating staff 28.

From the above it will be seen that depression of the operating staff 28 against the tension of the spring 36 will impart movement in a downward direction to the lower extremity of the arm 22 through the medium of the portion 28' and link 30, into an operative position. In order to retain the staff 28 in the depressed position a spring catch 37 is mounted on the inner face of the casing 26 as indicated at 38 for engagement in a cut-out portion or groove 39 formed in the staff 28'. When pressure is applied to the staff 28, it will be moved downwardly until the groove 39 engages the catch 37 thereby retaining it in the said position. A pair of spring members 40 are secured to the inner face of the casing 26 at a point substantially diametrically opposite the point at which the catch 37 is located and are directed against the staff 28' whereby to maintain the same in engagement with

the catch 37. The joint or hinge 23 being of the universal type allows of lateral as well as vertical movement of the arm 22, so that by a slight rotation of the handle 32 the arm 22 may be moved either to the channel 41 or the channel 42 as desired, when in a lowered position.

When operating the device, the motorman takes note of the position in which the switch is located, and then depresses the staff 28 through the medium of the handle 32 and at the same time slightly rotates the handle 32 until the extension 24 carried by the arm 22 is engaged in the desired channel, whereupon he starts the car. As set forth above the depression 39 has at this time engaged with the catch 37 and the arm 22 will be retained in a downward position while the extension 24 comes into engagement with one or the other of the blocks 47 and 48. The forward movement of the car, will then cause the block engaged, to be drawn with the car for a limited distance sufficient to close an electric operating circuit to throw the switch point 4 to the desired position.

In order to automatically disengage the extension 24 carried on the arm 22, the abutments 43 and 44 have been provided one of which engages the lug 25 on the arm 22 causing a pressure in an upward direction on the said arm. This pressure will be transmitted through the medium of the link 30 to the portion 28' of the staff 28 and this staff being pivoted at 29 will move laterally against tension of the springs 40 to disengage the groove 39 from the catch 37 and allow the staff 28 to be drawn upwardly by the tension of the spring 36 into normal position, carrying the arm 22 with it. It will thus be seen that the actuating members are automatically disengaged from the switch operating mechanism and returned to normal position without any move on the part of the operator.

In order to electrically operate the switch point 4 I employ a plurality of electrical circuits capable of being closed by the movable blocks 47 and 48 when properly engaged.

As shown in Fig. 2 a pair of stationary circuit terminals are provided on each of the channel members 41 and 42 as indicated at 45 and 46, respectively, these circuit terminals being insulated in any suitable manner from the channels 41 and 42. Each of the terminals 45 and 46 is adapted to be engaged by the movable circuit terminals 47 and 48, respectively, each of said circuit terminals being slidably mounted in the channel members 41 and 42 as previously pointed out. A pair of electrical circuits indicated by the numeral 49 are provided, the terminal wires of each circuit being connected in their proper relation to the respective circuit terminals 45, 46, 47, and 48. In

Fig. 2 the relative arrangement of the two circuit terminals is clearly illustrated, the action of both of the slidable circuit terminals 47 and 48 being substantially alike. I will therefore describe that of but one of them. The circuit terminal 47 comprises a block having a pair of laterally extending pins 50 carried thereby for engagement in complementally formed elongated apertures 51 in the side walls of the channel member 41. In order to retain the movable circuit terminal 47 remote from the stationary circuit terminal 45 I have provided a pair of retractile springs 52 anchored at 53 to the walls of the channel 41 and connected at 54 to the pins 50 as indicated in Fig. 2.

A pair of solenoid magnets 56 and 57 are provided one in each of the circuits 49 and are energizable when the circuit closers are actuated, any suitable source of electrical energy being provided, an electric battery being designated at 58. Each of the solenoid magnets 56 and 57 is in pivoted connection at 59 with the switch point 4 so that when one or the other of the solenoid magnets is energized the switch point 4 will be moved.

In operation the motorman or operator on the vehicle actuates the staff 28 in the manner previously described, the extension 24 being thus brought into engagement with one or the other of the circuit closers 47 and 48 causing the latter to engage the stationary circuit terminal 45 or 46 as the case may be whereby to energize the respective electric magnets controllable thereby, and thereby move the switch point 4 to the desired position.

While I have shown and described my invention as possessing a peculiar form and construction, it is desired that it be understood that I may make such changes in the details thereof that do not depart from the spirit and scope of the invention as claimed.

Having thus described my invention what I claim and desire to secure by Letters Patent is:

1. An automatic switch operating device, including guide ways, a fixed contact arranged in each of said guide ways, movable

contacts arranged in each of said guide ways, and means for engaging the movable contact with said fixed contact.

2. An automatic switch operating device, including guide ways, a fixed contact arranged in said guide ways, a movable contact arranged within said guide ways, electro magnetic means associated with the switch point and connected with said contacts, and means for engaging the movable contact with said fixed contact.

3. An automatic switch operating device, including a body portion, a guide-way formed in said body portion, a fixed contact arranged in said guide-way, a movable contact disposed in the guide-way, means for engaging the movable contact with the fixed contact, and means arranged adjacent said fixed contact for causing the engaging means to be automatically released from the movable contact, at times.

4. An automatic switch operating device, including a body portion, a guide-way formed in said body, a fixed contact arranged in said guide-way, a movable contact in the guide-way, means for engaging the movable contact with the fixed contact, and a curved abutment arranged adjacent said fixed contact for causing the engaging means to be automatically released from the movable contact, at times.

5. An automatic switch operating device, including, in combination with electro-magnetic means arranged in proximity to the switch point, a body portion, a guide-way formed in said body portion, a fixed contact arranged in said guide-way, a movable contact in the guide-way, means for engaging the movable contact with the fixed contact to magnetize said electro-magnetic means for operating the switch point, and a curved abutment arranged adjacent said fixed contact for causing the engaging means to be released from the movable contact, at times.

In testimony whereof I affix my signature in presence of two witnesses.

RAFAEL ALCOLEA.
